FOURTH TO JOHN A. OSBORN, OF DAY DAWN, WESTERN AU-
STRALIA, AUSTRALIA.

VEHICLE-SPRING BUFFER.

No. 842,001.

Specification of Letters Patent.

Patented Jan. 22, 1907.

Application filed November 6, 1905. Serial No. 286,006.

To all whom it may concern:

Be it known that I, PETER MCKAY, a subject of the King of Great Britain, and a resident of Day Dawn, Murchison, West Australia, have invented a new and Improved Vehicle-Spring Buffer, of which the following is a full, clear, and exact description.

This invention relates to improvements in devices for use in connection with vehicle-springs to relieve the springs from sudden jars under heavy loads, thus preventing breaking of the springs, the object being to provide a device of this character that may be readily placed in position and firmly held.

15 I will describe a vehicle-spring buffer embodying my invention and then point out the novel features in the appended claims. Reference is to be had to the accompanying drawings, forming a part of this specification, in which similar characters of reference indicate corresponding parts in all the figures.

Figure 1 is a side view of a vehicle-spring buffer embodying my invention, showing it as attached to a spring. Fig. 2 is a sectional elevation thereof, and Fig. 3 is a section on the line 3 3 of Fig. 2.

Referring to the drawings, 5 designates a vehicle-spring on which a buffer embodying my invention is secured. This buffer comprises a tube 6, the lower end of which is secured in a channel formed in a plate 7, placed on the upper side of the spring, and telescoping with said tube 6 is an upper member, consisting of an inner tube 8, which engages against the inner side of the tube 6, and an outer tube 9 engages against the outer side of said tube 6. The upper ends of said tubes 8 and 9 are secured in an annular channel formed in a cap-plate 10 and are held apart at the upper end by a spacing-ring 11. The tube 6 is provided with opposite vertically-disposed slots 12, and screw-bolts 13 engage in tapped holes in the tube 9 and have reduced end portions which pass through said slots 12 and impinge against the inner tube 8. These screw-bolts prevent the upper member from moving too far upward.

Attached to the lower end of the inner tube 8 is a metal disk 14, designed to engage against a buffer-block 15, consisting of rubber, and supported on the plate 7. Mounted

on the cap-plate 10 is a cushion or buffer, which is shown as hemispherical, and this buffer consists of a block 16 and a cap-piece 17, the said cap-piece 17 being of somewhat softer rubber than the rubber forming the block 16. Therefore when the upper portion 17 is torn away it may be readily removed and another piece cemented to the block 16. The upper buffer or cushion is removably held in place by means of screws 18, which pass through lugs 19, extended upward from the cap-plate 10, and impinge against the said upper cushion or buffer.

The device is held in place on the spring 5 by means of clip-yokes 20, which engage at their upper portions in transverse grooves 21, formed in the plate 7, and the lower portions engage with plates 22, placed against the under side of the spring 5. It will be noted that the ends of the plates 22 are inclined upward and outward, thus practically forming cam-surfaces, so that the clip-yokes by being forced downward thereon will draw the parts closely together. The plates 22 are mounted on an axle 23, and threaded extensions 24 on the clips 20 engage with a plate 25, which passes across the under side of the axle 23, and these threaded extensions 24 are engaged by nuts 26, which are prevented from accidental detachment by spring-yielding locking-plates 27.

In the operation when the spring 5 is forced downward by the load in the vehicle a wear-plate 28 on the vehicle will engage with the upper cushion or buffer, forcing the upper members downward into contact with the buffer-block 15. This of course will relieve the main spring 5 from undue pressure.

Having thus described my invention, I claim as new and desire to secure by Letters Patent—

1. A vehicle-spring buffer comprising tubular telescopic members, a cap-plate on the upper member having upwardly-extended tapped lugs, a rubber cushion seated on said cap, and screws engaging in said tapped lugs and engaging against said cushion.

2. A vehicle-spring buffer comprising a plate, designed to be secured to the upper side of a vehicle-spring, a tube extended upward from said plate and having opposite slots, the upper member comprising an inner

tube and an outer tube engaging respectively against the inner and outer sides of the first-named tube, screw-bolts passing through the said outer tube and through the slots of the 5 first-named tube, a cap-plate on the upper member, and a cushion mounted on said cap-plate.

3. A vehicle-spring buffer comprising a plate adapted to rest on the upper side of a 10 vehicle-spring, a tube extended upward from said plate and having opposite slots, upper tubes having sliding movement on the first-named tube, a metal plate carried by said upper tubes, a rubber cushion in the 15 first-named tube and adapted to be engaged by said metal plate, and a rubber cushion carried by the upper tubes.

4. In a vehicle-spring buffer, a plate adapted to be placed on the upper side of a 20 vehicle-spring and having transverse grooves,

a telescopic buffer mounted on said plate, a plate for engaging against the under side of the vehicle-spring and having cam-shaped ends, clip-yokes through which the spring passes, the upper portions of said yokes 25 engaging in said grooves of the first-named plates, while the lower portions engage with the cam-surfaces of the lower plates, threaded extensions on said yokes, and a bar engaging against the under side of the vehicle-axle, 30 and to which said threaded extensions are connected.

In testimony whereof I have signed my name to this specification in the presence of two subscribing witnesses.

PETER MCKAY.

Witnesses:

JAMES BARNES,
Wm. PALFREYMAN.
